UNITED STATES PATENT OFFICE.

CHARLES H. DOWNES, OF JERSEY CITY, NEW JERSEY.

STYLOGRAPHIC FOUNTAIN-PEN.

SPECIFICATION forming part of Letters Patent No. 232,633, dated September 28, 1880.
Application filed July 24, 1880. (No model.)

To all whom it may concern:

Be it known that I, CHARLES H. DOWNES, of Jersey City, in the county of Hudson and State of New Jersey, have invented certain 5 new and useful Improvements in Stylographic Fountain-Pens, of which the following is a specification.

The object of my invention is to improve stylographic fountain-pens, first, by the employment of a beveled tube, which is pointed like a "quill" pen, in combination with a needle or clearer, which is allowed to receive endwise motion, and which passes from an ink-receptacle directly through said quill or 10 writing-tube, as will be hereinafter explained; second, in a writing-point which is made separate from the "point-section" of the pen-handle, and so formed that it can be fitted tightly in its place in the point-section and 15 readily removed therefrom when it is desired to replace one writing-point by another one, as will be hereinafter explained. I attain these objects by the means illustrated in the annexed drawings, in which—

25 Figure 1 is an external view of my improved pen. Fig. 2 is an external view of the writing-point detached from the point-section. Fig. 3 is an enlarged sectional view of the fountain-pen, the upper part of which is broken 30 away. Fig. 4 is an enlarged sectional view of the writing-point.

Similar letters refer to similar parts throughout the several views.

A designates a small tube, which may be 35 made of any suitable metal or combination of metals, and which has a writing-point formed by beveling one end, as shown at *a* in the annexed drawings.

When the small tube A is finished it resembles a very small writing pen or quill with a tubular sheath, and, if desired, its point may be slotted and tipped with platinum, iridium, or other suitable metal. This writing-point A is suitably secured into a cylindro-conical portion, B, which may be made of hardened rubber, metal, or other material adapted for the purpose, and its cylindrical portion may or 45 may not have a screw-thread formed on it.

The portion B, having the tubular pen or 50 quill fixed in it, as shown, is applied tightly,

but removably, to the tapered end of a point-section, C, which is tubular, and which is applied to the hollow fountain-handle D of the pen.

E designates an air-tube which is arranged 55 in the ink-receptacle, and which communicates with the external air near its upper end. The air which tube E receives is discharged into the ink-receptacle at *b*, for the purpose of allowing ink to flow from the writing-point during the act of writing.

The lower portion of the air-tube E has a 60 needle or clearer, *c*, suitably applied to it, which is allowed to receive free endwise movement for the purpose of inducing a flow of 65 ink to the writing-point and for keeping the sheath of the quill free from clogging.

The needle or clearer *c* may or may not be 70 tipped with iridium or other suitable substance, and it extends down through the tubular portion or sheath of the quill A and protrudes slightly from the beveled writing-point of this tube, as clearly shown in several views of the drawings.

If the needle *c* is tapered, as shown in Fig. 75 3, and a corresponding tapered bore is formed in the point-section or writing-point, the needle, when in repose, will be seated like a valve in the point-section or writing-point, and thus prevent the escape of any ink therefrom when 80 the pen is not in use.

It will be seen from the above description that I have invented a fountain-pen the writing or pen point of which will be constantly 85 and freely supplied with ink from the reservoir-handle during the act of writing. It will also be seen that the pen can be provided with a writing-point as fine or coarse as may be desired, and that the point may be slotted like a common writing-pen, so as to afford a degree 90 of flexibility and the facility of making coarse or hair lines.

By the second feature of my invention an impaired or useless writing-point can be readily detached from the point-section C and a 95 new writing-point substituted.

In practice I shall sometimes dispense with an air-tube, E, as I find that air will enter at the beveled end *a* of the quill in sufficient quantities to allow the ink to escape freely 100

from the reservoir. I shall also form the point-section C on a rod, on which it will be vulcanized, thus saving expense of boring it out. The section B may also be formed in the same manner.

Having described my invention, I claim—
The beveled tube or writing-quill A, com-

bined with a point, B, and adapted for use with a point-section and a needle or clearer of a fountain-pen, substantially as described. 10

CHARLES H. DOWNES.
